In Great Britain April 1, 1943

4 Claims. (Cl. 271—59)

1

This invention comprises improvements in or relating to apparatus for registering sheets being fed to printing presses or other machines.

The invention is mainly concerned with sidelay registration of the sheets by mechanism comprising a drawbar which is located at the upper surface of the layboard or other sheet supporting board and is movable laterally below a sheet positioned at the front lays, and a drop-roller arranged to be spring-pressed into contact with the upper surface of the sheet immediately over the draw-bar so as to provide a nip between the roller and the bar at which the sheet is gripped and so moved with the bar up to a registering gauge. With the above mechanism there is no bodily lateral movement of the drop-roller; the axis of the roller remains stationary while contact between the roller and the sheet is maintained. In another form of sidelay registering mechanism top pressure is applied to the sheet by means of a gripper arranged to move bodily to and fro in a lateral direction with the draw-bar and in that case the gripper need not be in the form of a roller. The present invention is applicable to either of the above forms of sidelay registration mechanism, both of which will hereinafter be referred to generically as "sidelay registration mechanism of the type described."

Usually in mechanism of the type described the draw-bar, which is let into the surface of the layboard, extends across the whole width of the latter and the top pressure member and associated sidelay or gauge is a separate unit adjustable across the layboard so as to accommodate sheets of different width, the top pressure member co-operating with different positions in the length of the draw-bar depending on the particular setting of the member across with width of the board.

The present invention provides sidelay registration mechanism of the type described in which the top pressure member, whether a drop-roller or a gripper member mounted for bodily lateral movement with the draw-bar, the registering gauge, and a comparatively short length draw-bar in the form of a thin flexible blade-like element, for example of spring steel, are built up with a base-plate adapted to rest on the sheet supporting board, as a self-contained structure adjustable bodily as a unit in a direction across the width of the layboard, and if desired also in the direction of its length. With this construction the draw-bar need only be sufficiently long to provide a nip between the top pressure member and the bar and where the top pressure

2

member is a conventional drop-roller, to maintain the nip between the roller and the bar for such time as is necessary to draw the sheet up to the lay.

5 The base-plate is according to a feature of the invention provided with a shallow groove in which the draw-blade is accommodated for movement with the upper surface of the blade substantially flush with the upper surface of the base-plate. Preferably the unit also embodies a smoother arranged to be raised and lowered in timed relationship with the corresponding movements of the drop-roller or other top pressure member.

10 The foregoing and other features of the invention (some of which relate in particular to the operation of a drop-roller and smoother) are embodied in an arrangement of side-lay registration mechanism which will now be described 15 by way of example with reference to the accompanying drawings which are to some extent diagrammatic and in which:

Figure 1 is a perspective view of the sidelay mechanism,

20 Figure 2 shows details of the sidelay mechanism which are hidden from view in Figure 1,

Figure 3 is a view from the back showing an alternative arrangement to the arrangement shown in Figures 1 and 2, and

25 Figure 4 is a perspective view from the back, showing the unit illustrated in Figure 3 in position on a front plate.

30 In the construction shown in Figures 1 and 2 a square bar 101, has pinned to it a lever 102, and is caused to oscillate in a tube 104 by movement of a chain (or rod) 113. A collar 105 is slidably mounted on the bar 101, and has a downwardly extended arm 106, which passes through a longitudinal slot cut in the bottom of the tube 35 104. The end of the arm 106 engages one arm of a bell-crank lever 107 through the medium of a joint 108. The lever is pivoted from a stud 109, and the other arm of the lever has a roller 110 running on stud 111 mounted at its end and a further extension of the arm provides a bearing for 40 a pivot 112 mounted in link 113, the other end of the link engaging a pivot 114, which is fixed to an undertongue or draw bar 115. It will be seen from the above that oscillation of lever 45 102 will provide a reciprocating motion to the undertongue 115, which works in a groove cut in a plate or board 140. A lever 116 is pivoted from stud 117 and carries a roller 118 constituting the 50 presser member. A cam plate 119, is mounted on the lever 116, and is positioned above roller 110.

One end of the plate 119 is formed to engage a catch 120, pivoting from stud 121 fixed to the body bracket 122. The lever 116 is urged downwards (i. e. to bring the roller 118 into engagement with the undertongue) by a spring 123 on spring rod 124 which engages a pivot pin 125 at one end, the other end of the rod passing through an adjusting nut 126, which is screwed into the bracket 122 and which provides a reaction abutment for the spring. The roller end of lever 116 has an extension which houses a spring rod 127 and forms an abutment for the spring 128 and the adjusting nut 129. The rod 127 is pivoted at its lower end from a pin 130 mounted in the smoother plate 131. The plate 131 has two arms 132 and 133, which project behind a gauge bar 134, and are pivoted from pins 135 mounted in two blocks 136 attached to the bar. The plate has a hole cut in it to allow passage of the roller 118, and an upward extension of arm 133 is arranged to abut against adjusting screw 137 mounted in the body bracket 122. The gauge bar 134 is pivoted from a stud 138, a spring-washer 139 keeping it in close contact with the base plate 140. Angular adjustment for the bar is provided by an eccentric sleeve 141, mounted on a stud 142, which is fixed in plate 140. A clamping nut 143 secures the gauge bar in position after adjustment. The body bracket 122 is slidably mounted on the tube 104, and can be clamped to this tube by means of screw 144. Fine adjustment is provided for the position of the sidelay by the screw 145 and nut 146 mounted in the clamp 147, which is slidably mounted on tube 104, and clamped to this tube by screw 148.

The sidelay functions as follows, and as a starting point it will be assumed that the position is that shown in Figure 1, i. e. the lever 107 is at the limit of its forward stroke with the cam 119 resting on the roller 110, the catch 120 unlatched from the cam 119, and the roller 118 with its smoother plate 131 slightly raised above the sheet which is about to be sidelayed. The lever 107, after reaching the limit of its forward idle stroke reverses and makes a return working stroke moving the undertongue 115 towards the gauge bar 134. The cam 119 contacting the roller 110, is allowed to fall carrying with it the lever 116 and the roller 118, and also the smoother plate 131. This plate is adjusted to be slightly in advance of the roller 118, so that the latter does not project below the plate until the plate is stopped in its downward travel by the screw 137. Thereafter the roller 118 passes through the hole in the plate until it contacts the sheet and presses it against the moving undertongue 115. The pressure on roller 118 is adjusted by the nut 126 to suit the paper or material being worked and is such that when the edge of the sheet reaches the gauge bar 134, and offers increased resistance to movement the undertongue may slip on the sheet and the roller will cease to rotate. The grip on the sheet is such that the sheet is not buckled against the gauge bar. Toward the end of the pulling stroke of the lever 107, the roller 110 contacts the rear incline of the cam 119, lifting the roller 118, lever 116 and the smoother plate 131 clear of the sheet, and allowing the catch 120 to latch into position; thus, when the lever 107 makes its idle forward stroke, these parts will be prevented from coming down on the sheet. At the end of the forward stroke of the lever 107, the catch 120 is unlatched by the roller 110. The cam 119 then falls on to the roller 110 ready

for the operation of sidelaying the following sheet.

Figure 3 shows an alternative method of supporting the sidelay above the layboard by utilizing an angle section bar 104a, in place of the tube 104 shown in Figure 1. This arrangement has the advantage that it more positively locates the sidelay mechanism in relation to the layboard. It also has the advantage that it permits a limited degree of vertical adjustment of the unit to enable the base plate to seat upon the sheet supporting board irrespective of any slight variations there may be on the level thereof.

It is an advantage of the construction described above that the side registration of the sheets may be effected nearer to the front of the layboard than is possible with the usual mechanism.

It will be appreciated that the whole mechanism comprising the base plate, the side registering gauge, the draw-blade or bar, the drop-roller, the smoother and their actuating parts is built up as a self-contained unit which rests upon the layboard or front plate and is bodily adjustable across the width of the machine without modification of the surface of the layboard. With such a construction it is only necessary that the draw-blade should be sufficiently long to ensure maintenance of the nip between the drop-roller and the blade for a time necessary to effect movement of the sheet up to the gauge. It will also be appreciated that on account of the unitary construction of the sidelay mechanism, provision may readily be made for adjusting the position of the unit fore and aft in the length of the layboard, such adjustment being desirable in certain cases. One way of providing for such fore and aft adjustment is shown in Figure 4, two brackets 150 (only one is shown) support the bar 104a at opposite sides of the layboard and is adjustably held by bolts 151 in slots 152. The wire or rod 103 is attached to the arm 112 by a hook-plate 153 providing, within example, six positions of adjustment by hooking any one of the notches 154 over the pin 155.

On account of the fact that the pressure of the drop-roller is transmitted, through the draw-blade, to the same comparatively small area of the base-plate, there may be a tendency for undue wear to take place at that area. In order to avoid or minimise such a condition a special wear-resisting element, for example of Phosphor bronze, may be inserted into the base plate at the area in question, and if desired this insert may be arranged so as to be readily removable and replaceable.

It will be appreciated from the indication given at the outset of this description that the examples just described with reference to the drawings may be modified to apply the invention to the case in which top pressure on the sheet is effected by means of a gripper arranged to move bodily to and fro in a lateral direction with the draw-bar and that in such a case the gripper need not be in the form of a roller.

I claim:

1. Sidelay registration mechanism for a sheet-feeding machine and comprising as a unit, a side-registering gauge, a base-plate adapted to rest upon the surface of a sheet-supporting board or plate associated with front-lays, a draw-bar located at the upper surface of the base-plate with its length extending perpendicularly to the side-registering gauge and reciprocable in the di-

rection of its length below each sheet on the board in turn when the sheet is positioned at the front-lays, a top pressure member above the draw-bar and adapted to grip the sheet against the bar to cause the sheet to be moved by the bar, during the movement of the bar in one direction, up to the side-registering gauge, means for imparting reciprocal movements to the draw-bar and rising and falling movements to the pressure member in such timed relation that the pressure member is lowered on to the bar during the movement to draw the sheet up to the side-registering gauge and is then raised therefrom, a latch to hold the pressure member raised from the bar during the return, idle, stroke thereof, and means for releasing the latch near the end of the idle stroke to permit the lowering of the pressure member on to the bar during the next operative stroke.

2. Sidelay registration mechanism for a sheet-feeding machine and comprising as a unit, a side-registering gauge, a base-plate adapted to rest upon the surface of a sheet-supporting board or plate associated with front-lays, a draw-bar located at the upper surface of the base plate with its length extending perpendicularly to the side-registering gauge and reciprocable in the direction of its length below each sheet on the board in turn when the sheet is positioned at the front-lays, a top pressure member above the draw-bar and adapted to grip the sheet against the bar to cause the sheet to be moved by the bar, during the movement of the bar in one direction up to the side-registering gauge, means for imparting reciprocal movement to the draw-bar and rising and falling movements to the pressure member in such timed relation that the pressure member is lowered on to the bar during the movement to draw the sheet up to the side-registering gauge and is then raised therefrom, a latch to hold the pressure member raised from the bar during the return, idle, stroke thereof, means for releasing the latch near the end of the idle stroke, and cam means arranged to take control of the pressure member when the member has been released by the latch, to hold the member away from the draw-bar until the draw-bar has begun its working stroke and then to allow the pressure member to move into sheet-gripping relation with the draw-bar.

3. Sidelay registration mechanism for a sheet-feeding machine and comprising as a unit, a side-

registering gauge, a base-plate adapted to rest upon the surface of a sheet-supporting board or plate associated with front-lays, a draw-bar located at the upper surface of the base plate with its length extending perpendicularly to the side-registering gauge and reciprocable in the direction of its length below each sheet on the board in turn when the sheet is positioned at the front-lays, a top pressure member above the draw-bar and adapted to grip the sheet against the bar to cause the sheet to be moved by the bar, during the movement of the bar in one direction, up to the side-registering gauge, means for imparting reciprocal movement to the bar and rising and falling movements to the pressure member in timed relationship with the arrival of the sheet at the front-lays to grip each sheet in turn between the pressure member and the bar and thereby to move the sheet to the side-registering gauge, then to release the sheet and to return idly to the initial position, a hinged smoother plate, a resilient operative connection between the pressure member and the smoother plate whereby the latter is caused to rise and fall about its pivot with the pressure member and a stop limiting the downward movement of the smoother plate to the smoothing position but arranged to permit continued downward movement of the pressure member to contact the bar, by virtue of the resilience of the connection.

4. Sidelay mechanism as claimed in claim 3 in which the resilient relative movement of the smoother plate and the pressure member is limited and in which the stop is adjustable to a position in which the downward movement of the smoother plate is arrested before the pressure member, at the limit of its advance beyond the smoother plate, can engage the bar.
